ATTORNEY.

UNITED STATES PATENT OFFICE.

KARL BALTHASAR SCHÄFER, OF DÜSSELDORF-HOLTHAUSEN, GERMANY, ASSIGNOR
TO BALTHASAR MAASEN, OF BROOKLYN, NEW YORK.

ELASTIC HOLDER FOR LAMP-SHADES AND LAMP-GLOBES.

1,358,023.

Specification of Letters Patent.

Patented Nov. 9, 1920.

Application filed March 26, 1920. Serial No. 369,158.

To all whom it may concern:

Be it known that I, KARL BALTHASAR SCHÄFER, a citizen of the German Republic, and residing at Düsseldorf-Holthausen, 5 Germany, have invented certain new and useful Improvements in Elastic Holders for Lamp-Shades and Lamp-Globes, of which the following is a specification.

The present invention relates to an elastic holder for lamp-shades and lamp-globes and consists in the hereinafter described peculiar arrangement of the edge of the holder, by which the lamp-holder itself is converted into an elastic carrier for the lamp-shade, 10 and is adapted to release the shade on a simple pressure with the fingers of one hand only, or to open, respectively, for receiving the shade, without any other part or manipulation being required. As the 15 new holder may be made in one piece, both its manufacture and its use are extremely simple.

In the accompanying drawing Figure 1 is a perspective view of the new lamp-holder 20 showing its manipulation. Figs. 2 and 4 are sections through the holder in two different operative positions, Figs. 3 and 5 are sections on the lines A—B and C—D, respectively, through the holders in the positions shown in Figs. 2 and 4, respectively. Fig. 6 is a modified form of the holder, shown partly in section.

To the yoke *a* is attached in any suitable manner a holder ring *b* of angle section 35 and made of elastic material. The cylindrical flange *b* of this ring is undulated at its edge, so that broad portions *d* and narrow portions *f* are formed. The broad portions *d* are slightly curved inward and do not 40 verge into the disk-shaped portion of the ring, but are extended upward and doubled over thus forming doubled projections *g*, the upper edge of which is likewise undulated, these undulations *h* being of an opposite 45 sense to those of the flange at *d*. The disk-shaped portion *i* of the ring may be made in one piece with the cylindrical flange, as shown in Figs. 1-5. The cylindrical flange with the portions *d* and *g* may, however, 50 also be separately formed and secured to said disk-shaped ring *i*.

An inward radial pressure against the portions *g* will force the portions *d* outwardly,

spreading them as shown in Fig. 4. The radial spreading of the portions *d* is possible 55 because the extending of the periphery of the cylindrical portion caused thereby is compensated by the simultaneous radial inward contraction of the narrow portions *f* of the flange (Figs. 4, 5). The necessary radial pressure against the extensions *g* may be 60 effected simultaneously by the fingers of one hand. The portions *d* will then spread in such a manner and to such an extent, that the rim of the shade may be engaged into 65 the holding ring (Fig. 4). As soon as the portions *g* are released, the undulations *d* spring back and engage over the rim of the shade, holding the same in position.

The modified form of the ring according 70 to Fig. 6 acts in the same manner; here the undulated cylindrical ring is made in one piece with a holder cap *k*.

I claim:

1. In combination with a lamp socket, a 75 shade holder engaged therewith, and including an elastic ring, having circumferentially spaced flanged portions on its perimeter, extending upon opposite sides of the ring, and in substantially parallel relation to the 80 ring axis, said flanged portions capable of being radially flexed to clampingly engage one edge of each flanged portion with the lamp shade or disengage the same from said shade.

2. In combination with a lamp socket, a shade holder engaged therewith, and including an elastic ring having a continuous flange on its perimeter with portions thereof projecting in relatively opposite directions from said ring, the flanged portions extending upon one side of the ring, adapted 90 for clamping engagement with the lamp shade, and being releasable by an inward radial pressure upon the corresponding portion of the flange projecting upon the opposite side of the ring.

3. In combination with a lamp socket, a shade holder engaged therewith, and including an elastic ring having portions bent 100 upon themselves, and extending from one side of the ring, the free edges of said bent portions extending beyond the opposite side of the ring and inwardly curved to engage a lamp shade, said bent portions of the ring 105 affording finger engaging parts, whereby

the ring may be radially flexed and operatively engaged with or disengaged from the lamp shade.

4. As a new article of manufacture, a shade holding element for lamps, consisting of a resilient disk having circumferentially spaced portions each extending upon relatively opposite sides of the plane of said disk and radially yieldable by an inward pressure upon said portions at one side of

the disk to engage said portions at the opposite side of the disk with the lamp shade, or disengage the same therefrom.

In testimony whereof I affix my signature in presence of two witnesses.

KARL BALTHASAR SCHÄFER.

Witnesses:

JOHANN CARL SCHÄFER,
ANTON GREISS.
